UNITED STATES PATENT OFFICE.

KATHERINE E. BURNS, OF NEW YORK, N. Y., ASSIGNOR TO FRANKLIN SIMON & CO. INC., OF NEW YORK, N. Y., A CORPORATION OF NEW YORK.

DESIGN FOR A DRESS.

Application filed July 28, 1927. Serial No. 22,897. Term of patent $3\frac{1}{2}$ years.

To all whom it may concern:

Be it known that I, KATHERINE E. BURNS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by ornamental lines presenting a series of V-shaped members at the center of the front merging into circumferential

lines at the sides and the back, together with an ornamental belt and cuffs having the same general appearance with ornamental tucks on the shoulders.

Figure 1 is a front view of a dress, showing my new design, the same being shown on a figure illustrated by dotted lines.

Figure 2 is a rear view of the dress shown in Figure 1.

I claim:

The ornamental design for a dress, substantially as shown and described.

KATHERINE E. BURNS.
